UNITED STATES PATENT OFFICE.

JOHN M. WILSON, OF MONTGOMERY CITY, MISSOURI.

FRAME-CLAMP.

SPECIFICATION forming part of Letters Patent No. 433,506, dated August 5, 1890.

Application filed April 11, 1889. Serial No. 306,811. (No model.)

To all whom it may concern:

Be it known that I, JOHN M. WILSON, of 5
Montgomery City, in the county of Montgomery and State of Missouri, have invented
certain new and useful Improvements in
Frame-Clamps; and I do hereby declare the
following to be a full, clear, and exact de-
scription of the invention, such as will enable
others skilled in the art to which it apper-
tains to make and use the same.

My invention relates to an improvement in
clamps for picture-frames or similar articles
requiring accurate and nice joints.

The object is to provide a clamp capable of
15 receiving and holding frames of various sizes
while the frame is being fitted and its parts
are being nailed or secured together. With
this end in view my invention consists in cer-
tain novel features of constructions and com-
20 binations of parts, as will be hereinafter fully
described, and pointed out in the claims.

In the accompanying drawings, the figure
is a view in plan of my improved frame-
clamp.

25 A A' represent a pair of parallel bars, the
former of which has the guides 1 1 secured
thereto, while the latter is loosely mounted
on the guides, and adapted to slide back and
forth thereon as the exigency presents itself.
30 Thus the bar A is fixed and the bar A' is
movable, and the movement of the latter is
effected through a screw-threaded rod 2 pro-
jecting from bar A, where it is swiveled,
loosely through bar A', and the head 3 on the
35 rod, by being turned, forces the bar A' in-
ward or toward its mate, or outward, or else
holds it in the required position after it is
placed in position to hold the frame.

The bars A A' are furnished with undercut
40 grooves 4 4 on their sides and the frame-
holders or blocks 5 5, loosely mounted on the
bars, have corresponding depending ears 6 6,
which fit in the grooves and prevent any
movement except end movement. The bars
45 are divided for convenience in setting the
frame-holders or blocks by means of gradu-
ated scales 7 7, representing inches and frac-
tions of inches to aid in placing the blocks or
holders at proper distances apart. The blocks

or holders are provided at diagonal points 50
with fixed lugs or posts 8 8, and at the out-
side corner with a removable angular corner-
piece 9. This piece fits in a recess formed
for it, and its lower end extends through the
block, where it is held rigidly in place, and 55
the holder or block itself held on by means
of set-screw 10, which, by impinging against
the lower end of the corner-piece, binds it
against the bar.

From the description it is seen that not 60
only may the bars A A' be moved apart in
one direction to the required distance and
held in place, but also that the holders or
blocks may be slid in the opposite directions
and locked in position, so that the parts may 65
be quickly accommodated to any sized frame.
Furthermore, it will be observed that the
corner-pieces 9 are removable. This is to
enable the frame-maker to make a kerf with
his saw through the joint in the event that 70
the latter is imperfect after being cut in the
miter-box.

It is evident that slight changes might be
resorted to in the form and arrangement of
the several parts described without departing 75
from the spirit and scope of my invention;
hence I do not wish to limit myself to the
exact construction herein set forth, but—

Having fully described my invention, what
I claim as new, and desire to secure by Let- 80
ters Patent, is—

1. The combination, with fixed and movable
bars and means for locking them apart, of
frame-holders adjustably secured to said bars,
each frame-holder having rigid projections 85
and an intermediate removable projection,
substantially as set forth.

2. The combination, with fixed and movable
bars having graduated scales thereon and a
screw-threaded rod projecting from one and 90
passing through the other, of frame-holders
loosely mounted on the bars, and means for
holding them in place, said holders having
removable corner-pieces, substantially as set
forth.

3. The combination, with a pair of clamp-
ing-bars having undercut grooves on their
sides and means for locking them apart at

proper relative positions, of a set of frame-holders loosely mounted on the bars with ears extending into the grooves, removable corner-pieces, and set-screws for holding the latter in place and for locking the holders in position, substantially as set forth.

In testimony whereof I have signed this

specification in the presence of two subscriving witnesses.

JOHN M. WILSON.
